DESIGN FOR A TEMPORARY SEAL FOR THE ENDS OF TUBES

Felix Van Cleef, Chicago, Ill., assignor to Van
Cleef Bros., Chicago, Ill., a partnership

Application July 2, 1943, Serial No. 110,587

Term of patent 14 years

(Cl. 91—1)

To all whom it may concern:

Be it known that I, Felix Van Cleef, a citizen of the United States, residing at Chicago, in the county of Cook and State of Illinois, have invented a new, original, and ornamental Design for a Temporary Seal for the Ends of Tubes, of which the following is a specification, reference being had to the accompanying drawing, forming a part thereof.

In the drawing:

Figure 1 is a top perspective view of a tempo-

rary seal for the ends of tubes showing my new design;

Figure 2 is an edge view;

Figure 3 is an inverted or bottom perspective view; and

Figure 4 is a plan view thereof.

I claim:

The ornamental design for a temporary seal for the ends of tubes, substantially as shown.

FELIX VAN CLEEF.
